(57) **CLAIM**

The ornamental design for a candle cup, as shown and described.

DESCRIPTION

FIG. 1 is a first perspective view of a candle cup showing my new design, shown in a state of use;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1;

FIG. 9 is a perspective view of FIG. 1, shown in an alternate state of use;

FIG. 10 is an enlarged top perspective view of the candle cup; and,

FIG. 11 is an enlarged bottom perspective view of the candle cup.

The broken lines illustrate environment and form no part of the claimed design.

1 Claim, 11 Drawing Sheets
